CLAIM

The ornamental design for a container for an electronic device, as shown and described.

DESCRIPTION

FIG. 1 is a front perspective view of a container for an electronic device showing the new design;

FIG. 2 is another perspective view showing a rear thereof;

FIG. 3 is an elevation view showing a rear thereof;

FIG. 4 is an elevation view showing a front thereof;

FIG. 5 is an elevation view showing a right side thereof;

FIG. 6 is an elevation view showing a left side thereof;

FIG. 7 is a top plan view thereof; and,

FIG. 8 is a bottom plan view thereof.

Fine broken lines, which follow a contour of the container, illustrate stitching and are part of the claimed design.
